UNITED STATES PATENT OFFICE

2,552,867

ARTICLE STACKING AND TRANSFER
MECHANISMEarl J. Rapp, Toledo, Ohio, assignor to Lynch
Corporation, a corporation of Indiana

Application August 1, 1945, Serial No. 608,219

6 Claims. (Cl. 198—24)

1

This invention relates to a cartoning machine for butter and the like, and particularly to the mechanism for stacking wrapped bars of butter, such as quarter-pound size, so that two prints overlap two other prints for cartoning.

One object of the invention is to provide a mechanism for stacking the prints of butter two high and two wide comprising an intermittently operable conveyor and a ram which elevates the first two prints so that the next two can be fed to a position under them, and then elevates all four prints to a position where they may be pushed by another ram into the cartoning mechanism.

Another object is to provide a simple means to operate the conveyor and the rams in timed relation to each other so that the desirable arrangement of stacking is accomplished with a minimum of parts, the design of which is such that they are substantially foolproof in operation.

More particularly, it is my object to provide an article stacking mechanism which can be used for butter or any commodity, and which has an intermittently operable conveyor which conveys four prints of butter together so that two of them are positioned in a vertical ram, whereupon the conveyor stops when the ram raises, and then two more may be positioned in the ram, whereupon the conveyor again stops while the ram raises the four prints of butter to a position for discharge by another ram, the first ram then lowering to an initial position and the conveyor operating to bring four more prints of butter to a position for depositing on the first ram.

With these and other objects in view, my invention consists in the construction, arrangement and combination of the various parts of my machine whereby the objects contemplated are attained, as hereinafter more fully set forth, pointed out in the claims and illustrated in the accompanying drawings, wherein:

Fig. 1 is a perspective view of a butter printing, wrapping and cartoning machine including my invention;

Fig. 2 is an enlarged side elevation of a portion of the machine indicated by the bracket 2 adjacent Fig. 1 and showing the gear mechanism for operating the conveyor;

Fig. 3 is a plan view of Fig. 2;

Fig. 4 is a sectional view on the line 4—4 of Fig. 50, showing the parts in one position;

Figs. 5 and 6 are similar sectional views of a portion of Fig. 4, showing the parts in two other successive positions;

Fig. 7 is a sectional view on the line 7—7 of Fig. 6; and

Figs. 8 and 9 are vertical sectional views showing, respectively, a vertical ram-operating mechanism and a horizontal ram-operating mechanism.

2

On the accompanying drawings I have used the reference numeral 10 to indicate a pair of supporting castings for a transmission housing 12. The transmission housing 12 has a portion 14 which extends forwardly and terminates in a housing 16. The housing 16 supports a parchment wrapping mechanism which is described in detail in the copending application of Harold R. Coon and myself, Serial No. 593,708, filed May 14, 1945, the only difference being that in the present machine there is only one row of prints formed in the machine and issuing therefrom, whereas in the copending application a machine is shown for forming and wrapping two rows of prints.

15 Since many of the details of the print forming and wrapping mechanism and the cartoning mechanism are not essential parts of my present invention, I shall refer briefly to only a few of them, and throughout the drawings will use reference numerals from 10 to 899, corresponding to parts in the copending application, for reference thereto for any of the details which are omitted from the present specification. Reference numerals 900 and up will be used in connection with the present invention *per se*.

20 Adjacent the frame 16 is a second frame 18 for supporting cartoning mechanism. A motor 20 is shown for operating the entire machine in the manner disclosed in the copending application above referred to, and particularly for driving a main shaft 900 (which corresponds to the shaft 568 in the copending application), journaled in the frame 18, which shaft operates the mechanism of my present invention.

25 A butter hopper 154 is provided to receive butter or similar material to be formed into prints at a print forming die 224. The prints are then wrapped with parchment from a roll 370 by the mechanism mounted above the housing 16, the prints, after being wrapped, being discharged onto a platform 901 (see Fig. 3). The platform guides the wrapped prints to a pair of conveyor chains 902, the prints being pushed onto the chain by a ram 324 of the wrapping mechanism in groups of four. Each group of four is then conveyed by projections 903 so that they remain in groups of four, as shown in Figs. 2 and 4.

30 The conveyor chains extend around drive sprockets 904 and idler sprockets 905 and 906. There are two of the sprockets 906 to take up slack in the chains, and for this purpose they are journaled on arms 907 which may be clamped in various adjusted positions on a stationary rod 908 supported by a bracket 910. The bracket 910 is supported in rigid relation to the housing 18 and, together with a cross-bar 910a, supports chain guide bars 911. Between the chains 902, a plate 911a is supported by the bracket 910, 35 and the cross-bar 910a. The plate 911a serves

as a support for the prints of butter as they are carried forward by the projections 903.

The sprocket 904 is driven in the following described manner: The sprocket is mounted on a shaft 913 having thereon a gear 914 meshing with another gear 915. The gear 915 is secured to a sprocket 916 which is connected by a chain 917 to a sprocket 918. The sprocket 918 is mounted on a shaft 919, and also on this shaft is mounted a gear 920 having a pair of dwells 921 and 922. An idler sprocket 923 is provided for taking up slack in the chain 917.

Mounted on the main shaft 900 is a gear 924 having a pair of dwells 925 and 926 with a series of teeth 927 and 928 between the dwells.

Adjacent the drive sprocket 904 (see Fig. 4) is a vertical ram R having a pair of side plates 929 and 930, a bottom plate 931, and on the side plates a pair of ribs 932 and 933. The ram R is connected by a link 934 to a slide 935 which is slidably guided in a vertical guide 936. The slide 935 is connected by a link 937 with an arm 938 mounted on a rock shaft 939 (see Fig. 2). A second arm 940 on the rock shaft 939 is connected by a link 941 with a yoke 942 which slides on a guide block 943 on the main shaft 900. The yoke 942 carries a roller 944 which travels in a cam slot of a cam C. The cam groove has a low dwell section 945, a first riser section 946, an intermediate dwell section 947, a second riser portion 948, a high dwell section 949, and a drop section 950, the purpose of each of which will hereinafter be described.

Adjacent the ram R is a stationary support 674 having a pair of side plates 675 extending upwardly therefrom. The support 674 has a vertical wall 674^a and a horizontal wall 674^b. Four prints of butter are adapted to be pushed across the horizontal wall 674^b by a horizontal ram 660 as it moves toward the right from the position shown in Fig. 6, the four prints then being cartoned in the mechanism mounted on the frame 18 as disclosed in the copending application above mentioned, the present machine, however, being for cartoning one row of prints rather than two. The ram plate 660 is mounted on a rod 658 and driven by an arm 644 which rotates on the rock shaft 939. The arm 644 has a link 664 extending therefrom, as shown in Fig. 2, and this link terminates, as shown in Fig. 9, in a yoke 951 slidable on a guide block 952 on the main shaft 900, the yoke carrying a roller 953 for travel in the slot of a second cam C'. The cam C' has three sections, 954 a riser section, 955 a dwell section, and 956 a drop section.

Practical operation

After the prints of butter are deposited on the plate 911^a by the ram 324, four at a time, as shown in Fig. 4, the chains 902 advance so that one of their projections 903 engages the four prints and move them forward in the machine or to the right in Fig. 4. The conveyor has just stopped with four of the prints, numbered 1, 2, 3 and 4, in the position illustrated at the right-hand side of the figure. The prints 1 and 2 have passed under a hold-down bar 957 and the prints 3 and 4 are still under the hold-down bar. The prints 1 and 2 have also been slid onto the ribs 932 and 933 and stopped approximately against the vertical wall 374^a of the support 674.

The prints 1 and 2 are now supported by the ribs so that they may be lifted, as to the posi-

tion shown in Fig. 5, by elevation of the ram 931 from the Fig. 4 to the Fig. 5 position. This occurs while the cam C (Fig. 8) rotates clockwise through the distance 946, representing the first riser of the cam groove. At the same time, the gear 924 (Fig. 2) is rotating clockwise with its dwell 925 in contact with the dwell 921 of the gear 920. Thus the conveyor is held stationary while the ram is being elevated, and after elevation to the Fig. 5 position the teeth 927 of the gear 924 mesh with teeth 920^a of the gear 920 between the dwells 921 and 922 for advancing the conveyor to the position of Fig. 5. This causes prints 3 and 4 to slide onto the ram 931 under the prints 1 and 2 and below the ribs 932 and 933, as illustrated.

By this time the dwell 926 of the gear 924 is in contact with the dwell 922 of the gear 920, thus holding the conveyor stationary again for a somewhat longer period represented by the dwell 926 being longer than the dwell 925, and during which time the horizontal ram 660 is pushed toward the right in Fig. 6 for pushing all four prints, 1, 2, 3 and 4, across the horizontal wall 674^b of the support 674 and effecting the cartoning operation as disclosed in the copending application. When the prints 1, 2, 3 and 4 are almost completely on the wall 674^b the ram 931 drops from the Fig. 6 position to the Fig. 4 position. The horizontal ram 660 is moved forwardly by the roller 953 (Fig. 9) traversing the drop portion 956 of the cam C' and the roller 944 (Fig. 8) traversing the drop portion 950 of the cam C, the intermediate dwell portion 947, the second riser portion 948 and the high dwell portion 949 having been previously traversed by the roller 944 for causing the dwell of the ram 931 in the Fig. 5 position and then the rising of the ram to the Fig. 6 position and the dwelling of the ram at this position while the horizontal ram plate 660 moves the four prints onto the support 674. The dwell portion 955 of the cam C' in Fig. 9 holds the ram plate 660 in the position of Fig. 2 for the time period during which the vertical ram 931 has the four prints stacked thereon and is elevated to the proper position, as in Fig. 6, for the horizontal ram plate to push them into the cartoning mechanism. In the cartoning mechanism the four prints are cartoned, as already suggested, and the cartoned prints are fed out on a discharge conveyor 870.

My stacking mechanism is obviously simple of construction and operation, and the parts thereof are suitably timed so as to efficiently stack four prints of butter or other commodities so that they can be cartoned in the stacked position. Although I have described the mechanism as adaptable for four articles in a 2 x 2 stack, it can obviously be designed for other arrangements, such as 3 x 2, 3 x 3, etc. Changes of this character and others as well may be made without departing from the real spirit and purpose of my invention, and it is my intention to cover by my claims any modified forms of structure or use of mechanical equivalents which may be reasonably included within their scope.

I claim as my invention:

1. In a machine of the character disclosed, a vertically movable ram, a vertical wall adjacent the front side of said ram, a horizontal wall adjacent the top of said vertical wall, a conveyor adjacent the rear side of said ram for conveying a plurality of articles onto the ram to a position adjacent said vertical wall, said ram having supporting ribs to receive a plurality of such articles

at one elevation, means to raise said ram, said conveyor being operable to move another plurality of articles onto said ram in stacked relation to the first articles, means for further raising said ram to a position past said vertical wall with the top of the ram substantially aligned with said horizontal wall, and a second ram for moving all of said articles from said ram onto said horizontal wall.

2. In a machine of the character disclosed, a vertically movable ram, a conveyor adjacent said ram, said ram having supporting ribs to receive a plurality of such articles at one elevation, and a platform below said supporting ribs to receive a plurality of such articles at another elevation, means to raise said ram, said conveyor being operable to move a plurality of articles onto said ribs and another plurality of articles onto said platform, and means for simultaneously moving all of said articles from said ribs and platform.

3. In a machine of the character disclosed, a vertically movable ram, a vertical wall adjacent the front side of said ram, a horizontal wall at the top of said vertical wall, a conveyor adjacent the rear side of said ram for conveying a plurality of articles onto the ram, said ram having a first means to receive said plurality of articles at one elevation, means to change the elevation of the ram, said conveyor being operable to move another plurality of articles onto said ram, said ram having a second means to receive said second plurality of articles in stacked relation to the first plurality, means for further changing the elevation of said ram so that said articles are in a position past said vertical wall, and means for moving all of said articles from said first and second means of said ram and onto said horizontal wall.

4. Print stacking mechanism comprising a vertically movable elevator having upper and lower shelves for supporting pluralities of prints, conveyor means having one end terminating immediately adjacent a first side of said elevator and capable of transferring pluralities of prints in a horizontal direction onto said shelves when said shelves are aligned with said conveyor means, a stack supporting member closely spaced from a second side of said elevator and disposed at a higher level than said conveyor means, ram means movable horizontally to displace prints transferred to said upper shelf onto prints transferred to said lower shelf and to displace all said prints onto said supporting member in contacting stacked formation when said lower shelf is aligned with said supporting member, and actuating means for said conveyor means, said elevator and said ram means for initially aligning said shelves with said conveyor means, operating said conveyor means for transferring pluralities of prints from said conveyor means to said shelves aligned with said conveyor means, raising said elevator to align said lower shelf with said stack supporting member, and moving said ram to displace the prints transferred to said upper shelf onto the prints transferred to said lower shelf and also to displace all said prints onto said supporting member in contacting stacked formation when said lower shelf has been aligned with said supporting member.

5. Print stacking mechanism comprising a vertically movable elevator having upper and lower shelves for supporting pluralities of prints, a conveyor having one end terminating immediately adjacent a first side of said elevator and capable

of transferring pluralities of prints in a horizontal direction onto said shelves when said shelves are successively aligned with said conveyor, a stack supporting member closely spaced from a second side of said elevator and disposed at a higher level than said conveyor, a ram movable in a horizontal direction to displace pluralities of prints from said shelves onto said supporting member in contacting stacked formation when said lower shelf is aligned with said supporting member, and actuating means for said conveyor, said elevator and said ram for initially aligning said upper shelf with said conveyor, operating said conveyor for transferring a plurality of prints from said conveyor to said upper shelf aligned with said conveyor, raising said elevator to align said lower shelf with said conveyor, again operating said conveyor for transferring a plurality of prints from said conveyor to said lower shelf aligned with said conveyor, raising said elevator to align said lower shelf with said stack supporting member, and finally moving said ram to transfer said prints from said two shelves to said supporting member in contacting stacked formation.

6. Print stacking mechanism comprising a vertically movable elevator having upper and lower shelves for supporting pluralities of prints, a conveyor having one end terminating immediately adjacent a first side of said elevator and capable of transferring pluralities of prints in a horizontal direction onto said shelves when said shelves are successively aligned with said conveyor, a stack supporting member closely spaced from a second side of said elevator and disposed at a higher level than said conveyor, a ram movable in a horizontal direction to displace pluralities of prints from said shelves onto said supporting member in contacting stacked formation when said lower shelf is aligned with said supporting member, a stationary stop member extending vertically at the level of said conveyor but short of said stack supporting member at the side of said elevator opposed to said first elevator side for terminating print movement across said shelves short of the shelf edges, and actuating means for said conveyor, said elevator and said ram for initially aligning said upper shelf with said conveyor, operating said conveyor for transferring a plurality of prints from said conveyor to said upper shelf aligned with said conveyor, raising said elevator to align said lower shelf with said conveyor, again operating said conveyor for transferring a plurality of prints from said conveyor to said lower shelf aligned with said conveyor, raising said elevator to align said lower shelf with said stack supporting member, and finally moving said ram to transfer said prints from said two shelves to said supporting member in contacting stacked formation.

EARL J. RAPP.
